BARREL COLLET FOR MECHANICAL
PENCILS

Charles K. Lovejoy, Needham, Mass., assignor to
The Moore Pen Company, Boston, Mass., a
corporation of Massachusetts

Application March 1, 1946, Serial No. 651,207

4 Claims. (Cl. 188—67)

1

This invention relates to improvements in barrel collets for mechanical pencils.

In Patent No. 2,358,091 of September 12, 1944, I have disclosed a mechanical pencil in which the rod of lead is fed, step by step, by simple pressings and releasings of an exterior part of the pencil. Within the barrel is a collet having resiliently flexible prongs that rub on the rod, pointing a little forward from perpendicularity to the rod. These can bend to let the lead slip forward easily, but if the lead begins to move backward they jam between the lead and the barrel and so arrest regression of the lead. The present invention provides an improved structure of collet which may be used in that pencil, and can be used in other constructions of pencil, for permitting progression and preventing regression of the lead.

This invention eliminates the requirement that the prongs be made of material which is inherently resilient. Also it dispenses with annular integral supports for their ends. It permits of the prongs being stamped from thin plane non-elastic sheets, and of their being assembled loosely without further treatment. And, by making the bits in T-shape, it provides for their being held in ready position, without closing the axial hole when the barrel is empty of lead. These bits are combined with an annular shoe, backed by a simple helical spring, those yielding lets the lead-engaging ends of the prongs swing forward when dragged by forward feeding of the lead, but pushes them gently back into jam position endwise between the lead and the peripheral wall, to oppose regression of the lead, without it being necessary that the prongs should bend to allow forward movement, and become stiff in backward movement.

By this means uniformity of elasticity is assured in the prong action, both among those prongs that are assembled in a single pencil, and also among the assemblies of prongs in individual pencils that are made in mass production. Also, the invention facilitates the producing of any desired degree of resilience in the action of the prongs, whatever may be the size or the nature of the material composing the writing rod. Other advantages are that the durability of this important part of a mechanical pencil is increased; the processes of manufacture of the collet are simplified; and the costs are reduced.

Details of an illustrative construction, by which these benefits are attained, are shown in the accompanying drawing, in which

2

Figure 1 is a medial longitudinal section through a mid-portion of a mechanical pencil containing the barrel collet of the invention; and

5 Figure 2 is a cross-section through the collet portion of Figure 1 on a line 2—2 that passes between prongs.

For both figures the scale is greatly enlarged. While the invention is applicable to pencils of 10 any size, it in particular is intended for pencils of ordinary size whose outside diameter is a minor fraction of an inch.

In a complete pencil the prongs 10 of the collet are housed within a shell 12, which has annular walls within which an annular ledge 13 surrounds a deep well 14. This shell 12 has an inset lid 16, and is here represented as being fixed in position within the pencil barrel 18, by being seated at the junction of the cylindrical and 20 the tapering point parts of the barrel by a main operating spring 20 which bears downward around a boss 22 on the lid 16 and bears upward against an upper part (not shown) of a long tube 24 that surrounds the lead 26. When 25 the user presses this tube 24, by thumb pressure on its top, a collet at the bottom (not shown) grips and feeds the lead 26 a step downward, as can be seen in my said Patent 2,358,091.

The function of the barrel collet prongs 10 is to let the lead 26 be fed downward easily, but to oppose its moving upward. The tube 24 passes loosely through the shell 12 of the barrel collet. At the region illustrated, the lead 26 is loose within that tube. Slots 38 in the tube 24 provide ample clearance for the barrel collet prongs 10 to reach the lead. The prongs may be a single opposed pair, or, may be banked in multiple behind one another as illustrated, arranged on two or more sides of the lead, all operating together as a unit; but in either case there are stiff bits of sheet material confined loosely in radial grooves, within housing 12. They point a little forward of perpendicularity to the axis, the angle illustrated being about 5°. This angle might be greater or less, the critical feature being that each prong has length exceeding the radial distance from the side wall of the housing 12 to the rod of lead, and is too stiff to buckle past the perpendicular, when pressed upward by the lead.

50 As can be understood from the drawing, the shell 12 has a central well 14, with bottom axial hole 30 permitting free up and down movement of the tube 24; and has the bottom part of its 55 lid 16 resting on the ledge 13 around this well

to fill the housing 12 with an annular mass or body, of material, here shown as a boss on the lid 16 within the housing, in which there are two opposite radial recesses 34, each broad and high enough to contain and to hold loosely a group of the prongs 18. There is also an annular peripheral groove 36 on the peripheral outside of this mass, connecting with the radial recesses 34. The prongs are of T-shape, and the flanges of the head of each are engaged in the peripheral recess 36. Thus each T-head abuts the outer wall of the shell 12; and the leg of each T extends within a recess 34, and through a slot 38 in the tube 24, for its concave-ended foot to engage the rod of lead 26. Each individual prong fits loosely in these interior spaces, with the mid-portion of the group of prongs supported on the shoe 40, except that the length of each prong slightly exceeds the space which is open radially for housing it. Therefore each prong pitches slightly forward, in the direction of downward feed of the lead; but this pitch is held to a minimum by the annular shoe 40 pressed upward by a mild helical spring 44 that is strung on the sleeve 42 and is based on the bottom of the well 30. Therefore the prongs normally stand always in contact both with the housing shell 12 at their heads and with the rod of lead 26 at their feet. When the lead 26 is fed downward by the user of the pencil the spring 44 yields to let the prong feet that are in contact with the lead be dragged slightly downward, increasing their pitch and easing the movement of the rod of lead. At the same time the lid 16 prevents the head ends of the prongs from being lifted by the spring 44. But if the lead 26 begins to move upward, either by drag of the tube 24 in returning after being released by the user's thumb, or by pressure of the point of the lead on paper in writing, the drag is in direction to increase the friction between the lead and the feet of the prongs, and is aided by the spring 44 and its shoe 40 to make a jam of the prongs between the lead and the housing. Thus an incipient recession of the lead moves the prongs toward perpendicularity to the axis, with increase of friction and with operative opposition to more than incipient upward movement of the lead.

The collet prongs fit into their housing loosely enough to perform these movements without becoming stuck, and yet the shoe 40 always makes them tight enough to catch on the lead and oppose the upward movement of the lead relative to the barrel, as thus described. The prongs are preferably made of non-corrosive material. The flanges at their heads prevent them from slipping into the central hole when the lead is absent, and this device to hold their heads at the periphery dispenses with the need for making them integral parts of washers having con-

tinuous annular rims, leaving each of them free to rise and fall and shift its angle within the very small limits available, without requiring that there be a flexibility or any uniformity of resilience in the prongs themselves, all of which are preferably so stiff that they do not bend appreciably. While the drawing shows a considerable number of prongs in the assembly at each side of the lead, and shows them arranged in two opposing groups on a single diameter, construction is not limited in either of these respects, the radial directions in which the slots 34 extend, and the number of prongs assembled in each, being matters of choice.

I claim:

1. A collet for opposing regression of an axial rod of lead, comprising, in combination a bottomed shell with an axial hole for the rod; prongs housed by the shell; an annular mass of material within the shell, having an axial hole for said rod, and having radial recesses with side walls which lead from that axial hole to the peripheral wall of the shell; said prongs being bits of thin stiff sheet material set loosely in the recesses and having radial extent which slightly exceeds the radial distance from the axial hole to the peripheral wall of the shell; and a spring, within the shell, based on the bottom of the shell and set to press the axial ends of the prongs backward into said hole.
2. A barrel collet as in claim 1, further characterized in that there are mutually obstructive surfaces, on said mass and on said bits respectively, within the shell, arranged to limit movement of the loose bits toward the axis, thereby to hold the bits from closing the axial space.
3. A barrel collet as in claim 1, further characterized in that the bits are of T-shape, and there is peripheral space around said mass, connected with said recesses, for housing the heads of the T-bits, whereby the loose bits are restrained from filling the axial hole.
4. A barrel collet as in claim 1, in which the shell has a well below the prongs, and in the well there is a loose sleeve having an annular top shoe to engage the bits, the said spring being helical, strung on the sleeve, and based on the bottom of the well.
